UNITED STATES PATENT OFFICE

146,018

DESIGN FOR A BROOCH OR SIMILAR ARTICLE

Samuel Darvie, New York, N. Y.

Application April 5, 1946, Serial No. 128,318

Term of patent 3½ years

(Cl. D45—19)

To all whom it may concern:

Be it known that I, Samuel Darvie, a citizen of the United States of America, residing in New York, county of New York, and State of New York, have invented a new, original, and ornamental Design for a Brooch or Similar Article, of which the following is a specification, reference being had to the accompanying drawing, forming part thereof.

Fig. 1 is a plan view of a brooch or similar article showing my new design.

Fig. 2 is an edge view thereof.

I claim:

The ornamental design for a brooch or similar article, substantially as shown.

SAMUEL DARVIE.
